STRETCHER TOPPING AND TAKE-OFF BAR
FOR ELASTIC HOSIERY WELTS AND THE
LIKEEdward A. Mohr, Wyomissing, Pa., assignor to
The Nolde and Horst Company, Reading, Pa., a
corporation of Pennsylvania

Application November 30, 1935, Serial No. 52,287

3 Claims. (Cl. 66—147)

My invention relates to the knitting of hosiery or the like having a part thereof, as a separately made elastic garter welt, integrally united thereto by engaging loop stitches during the usual 5 knitting operation.

More particularly my invention relates to a novel stretcher bar adapted to removably hold the elastic welt tensioned by determined elongation and with an edge portion thereof freely 10 positioned for direct topping engagement with the knitting needles and supported in such stretched relation during the subsequent formation of the attached knitted fabric.

I am aware that the use of elastic welts is old 15 and that it has heretofore been interknit with a stocking; also, that by means of a usual transfer bar or ring, upon the points of which the elastic welt is first impaled, it may be transferred to the knitting needles when said points 20 are in superimposed relation.

It is the object of my present invention to 25 avoid the need of such costly tooled and more expensively maintained transfer devices and further to eliminate the added labor cost of such intermediate welt engaging operation, by directly 30 topping the welt upon the needles of the knitting machine by means of a simple and economically manufactured stretcher bar upon which the welt may be held in tensioned elongation for convenient topping, and further supported thereon in stretched relation to avoid strain upon the needles 35 during subsequent knitting.

With the above stated main object in view my 40 invention consists of a stretcher bar, the essential construction and manner of its use being more fully described in connection with the accompanying drawing, and its novel features specifically set forth in the appended claims.

Fig. 1 is a plan view indicating a preferred embodiment of my stretcher bar adapted for use 45 with a straight bank of needles as in a full-fashioned knitting machine, the needles being indicated by the line of small circles.

Fig. 2 is a transverse cross-sectional elevation 50 of the bar shown in Fig. 1, and its relative position to the needles and sinkers of a full-fashioned machine, shown diagrammatically, and a take-up tensioning connection indicated.

Fig. 3 shows in a perspective elevation, an embodiment of my stretcher bar adapted for a circular knitting machine.

Any suitable woven, braided, or knitted elastic 55 may be employed with my stretcher bar, and it may of course be engaged upon the needles anywhere in its width, but there is available special

elastic particularly adapted by a spaced selvage warp, or by selvage loops, for convenient topping engagement with the knitting needles. Fabric of the above nature is cut in such lengths that when stretched on my bar will insure adequate 5 tension for garter purposes and at the same time spacedly spread the topping portion for more convenient engagement with the needles.

Now referring particularly to Figs. 1 and 2, my stretcher bar 5 is shown as preferably made 10 from a simple flat strip of metal or other suitable material, with wide end portions 6, 6, having end serrations or impaling teeth 7, 7, and a reduced-width portion 7' intermediate said ends formed by cutting back one edge 8, the other edge 9 being shown with points or tits 10 at spaced intervals therealong, and take-up attaching devices as loops 11, 11 provided on such edge 9.

A suitable length of fabric, indicated by dotted 20 outline A, is shown as held in stretched position on bar 5, with its cut ends engaged by serrations 7, 7, its lower edge engaged by points 10, and its topping edge spanned between the ends 6, 6, and in free position, outside the edge 8 of reduced-width portion 7', so that it may be readily 25 topped directly upon the line of needles 12. Referring to Fig. 2, it will be seen that the cut back edge 8 of this embodiment is provided not only to conveniently free the welt topping edge 30 35 of the elastic, but as a clearance for the reciprocated sicker 15.

After the topping of the edge on needles 12, I prefer in most cases to hold the elastic welt in stretched condition to avoid the strain its retraction might put upon the needles, and to this end loops 11, 11 are provided for connection of the usual tension strap of the knitting machine, the bar being used to draw off the knitted fabric as it is produced, and the points 10, 10, it will be 40 seen now function to distribute the pull of the take-off on the bar 5 across the width of the welt. After the knitting has progressed sufficiently, the bar 5 may be removed for repeated use, and the take-off engaged with the knitted fabric 45 direct as heretofore.

The bar for the use above set forth, may be comparatively rigid, but when made of flexible material 5a and provided with a locking connection 20 as shown in Fig. 3, it may be bent with 50 the stretched fabric ends engaged thereon by serrations 1a, 1a into a ring for topping on the circle of needles of a round-and-round knitting machine. And for such latter purpose the wider ends 6, 6, the points or tits 10, and the take-off 55

engaging loops 11, 11, as shown in Figs. 1 and 2 may be omitted and the bar 5a made of the same width throughout with equal width serrated ends 1a as indicated in Fig. 3, with the topping-edge 5 of the welt somewhat projected beyond said width.

My improved stretcher bar, as above described, is intended to eliminate as unnecessary the step of topping the elastic welt on the points of a transfer or welt bar, but when use of such transfer bar is found desirable, my stretcher bar will 10 simplify and facilitate topping operation thereon.

The serrated or impaling teeth 7 at the ends of the bar may not be suitable for certain elastics, and other engaging means substituted, and 15 the bar may be otherwise modified for specific uses within the spirit of my invention as defined in the following claims:

What I claim is:

1. A stretcher bar for topping elastic welts and 20 the like upon the needles of a knitting machine, consisting of a flat bar having serrated ends adapted to engage and hold the welt in longi-

tudinally stretched position thereon, and a cut-back sinker-clearing intermediate portion of said bar adapted to freely expose a topping edge portion of the stretched welt.

2. A stretcher bar for topping elastic welts and 5 the like upon the needles of a knitting machine, consisting of a flat bar having serrated ends, a cut-back intermediate edge, and spaced fabric-engaging tits on the opposite edge, said serrated ends and edge tits being adapted to support a 10 welt in stretched position with its topping edge positioned adjacent said cut-back bar edge.

3. A stretcher bar for topping elastic welts and 15 the like upon the needles of a circular knitting machine, consisting of a flat flexible bar having engaging means to hold a free edge of the welt in stretched topping position thereon, and complementary means at the ends of said bar adapted to be engaged and hold said bar and its stretched welt bent to form a closed circle. 20

EDWARD A. MOHR.
